SAFETY RAZOR

Charles Dixon and Harold Julian Wilberforce
Raphael, London, England

Application March 30, 1935, Serial No. 13,962
In Great Britain February 15, 1935

11 Claims. (Cl. 30—46)

This invention relates to safety razors of the reciprocating blade type in which the movement is imparted to the blade through the medium of a friction roller and associated surfaces in the act of drawing the razor across the skin of the user.

One of the objects of the present invention is to provide an improved razor of the above type in which the usual method of mounting the friction roller on the cover plate is dispensed with.

A further object of the invention is to use in such improved razor a non-flexed double edged blade having an elongated aperture in it to clear the friction roller, the blade being located in the razor both longitudinally and laterally by said aperture.

The present invention in its broadest aspect consists of a safety razor of the type specified in which the friction roller is supported by the fixed base of the razor.

In one embodiment of the invention motion is imparted to the blade by a member which is slidable on the fixed base. In such an embodiment the blade is either supported by the upper faces of the fixed base or is supported by the slidable member.

In order that the invention may be clearly understood and carried into effect examples according to both such embodiments will now be described by aid of the accompanying drawings in which:

Fig. 1 is a perspective view of a complete razor according to either of the embodiments.

Fig. 2 is a composite perspective view showing the parts disassembled and the friction roller removed of a razor according to the embodiment in which the blade is adapted to be supported by the slidable member.

Fig. 3 is a longitudinal sectional view of the razor according to the embodiment illustrated in Fig. 2.

Fig. 4 is a transverse section on the line 4—4 of Fig. 3.

Fig. 5 is a perspective view, with the cover plate removed of a razor according to the other embodiment in which the blade is supported by the upper surfaces or guards of the fixed base.

Fig. 6 is a perspective view showing an alternative construction hereinafter to be described.

In the razor according to both embodiments illustrated the fixed base 1 is of channel section and provided with a pair of safety guards 2 extending laterally from opposite sides of the

channel, the whole being formed from a single sheet of metal.

A single friction roller 3 is employed having a pair of knurled or otherwise roughened surfaces 4, said surfaces being separated by a central cam groove 5. This roller has pintles 6 at opposite ends by means of which the roller is mounted to rotate within bearings in a pair of upstanding lugs 7 carried by and upset from the material composing the base 8 of the channel in the fixed base 1. The slideable or reciprocating member 9 is also of channel section the same being supported upon the base of the channel by the ends of the member's vertical side members 10 which are extended for the purpose beyond each end of the base proper 12 of the reciprocable member. The extended ends of the side members are spaced at such a width as to fit between the aforesaid friction roller supporting lugs 7 and the sides of the channel in the fixed base but slightly less than the width of the channel so as to permit the member to reciprocate freely without undue lateral movement. In the preferred arrangement shown the side members 10 are parallel throughout their length, so as to provide as long a lateral guiding surface as possible.

Beneath the base of the reciprocable member the base of the channel is cut to provide the material for the roller supporting lugs 7 and a slot 13 to permit of the longitudinal movement of a pin 14 extending from the underside of the base of the reciprocable member and serving, when formed or provided with an enlarged head 14a as a means for retaining the member within the channel recess in which it works for which purpose it engages beneath the lips 11 on opposite sides of the slot 13. Reciprocation is imparted to the reciprocable member by a driving pin 15 which extends upwards from its base into engagement with the aforesaid cam groove 5. The blade 16 for a razor as just described is formed with a central opening 17 of such a length and width as will permit the same to fit closely over the upstanding vertical sides 10 and in the first example across the extended ends of the reciprocable member, the support for the blade being afforded in such first example by the upper edges of cut outs 18 in the extremities of said extended ends and in the second example by the upper faces of the laterally extending guards 2.

The central opening in a blade for use in connection with the first example has its ends reduced in width as shown in Fig. 2 to provide

ledges 17a which engage within the aforesaid cut outs 18.

The usual hinged or otherwise movable cover plate 19 is cut out in the centre with an opening 20 to permit the friction roller to project therethrough when the cover plate is closed. The cover plate is also, if necessary, curved to provide a clearance above the upstanding sides of the reciprocable member and to permit the longitudinal edges thereof to close down in near proximity to the upper surface of a positioned blade.

In the alternative arrangement illustrated in Fig. 6 and applicable to either of the described embodiments, the aperture in the blade is formed with opposing projections 21 which engage in correspondingly shaped and positioned gaps 22 in the upper edges of the vertical side members 10. The engagement between the projections 21 and the gaps 22 ensures correct longitudinal location of the blade without excessive, if any, end play between the blade and the member 9. By suitably lowering the friction roller and increasing the distance inwards to which the projections extend, such projections may be made to engage in the cam groove 5 whereby the blade is directly driven, in which case the member 9 and the driving pin 15 may be dispensed with, the blade being supported directly upon the upper faces of the safety guards.

The depth of a razor constructed according to the present invention and therefore the diameter of the friction roller may be relatively small thereby effecting an increase in the speed at which the blade may be reciprocated without deviating unduly, if at all, from the normal cutting angle at which the razor is held in relation to the surface of the user's skin.

Although the razor according to this invention has been described as having a single friction roller with an interposed cam groove, more than one roller and cam groove may be used. Alternatively one or more cam surfaces at the end or ends of the roller or rollers may be employed instead of intermediate cam grooves.

What we claim is:—

1. In a safety razor, in combination, a fixed base of channel section having a laterally extending safety guard on each side thereof, roller supporting means extending upwards from the base of the channel, a friction roller revolubly mounted in said supporting means, said roller having a cam groove intermediate its length, a U-shaped reciprocable carriage slidably supported upon the base of the channel, the upstanding side portions of said carriage extending upwards to above the upper surface of the laterally extending guards, projecting means on said reciprocable carriage engageable with the cam groove in the friction roller, and a cover plate adapted to close down above a positioned blade and provided with an aperture through which the friction roller partially projects when the cover plate is closed.

2. In a safety razor, in combination, a handle, a fixed base mounted on said handle, safety guards extending laterally on opposite sides of said fixed base, a friction roller rotatably mounted on said fixed base and having a cam groove intermediate the length thereof, a carriage slidably mounted on said fixed base, a pin projecting upwards from said carriage adapted to engage said cam groove, a cover plate adapted to be closed down above the upper surface of the fixed base and a positioned blade, and provided with

an aperture through which said friction roller partially projects when said cover plate is in closed position, whereby rotation of the friction roller by rolling contact with the skin of the user imparts a reciprocatory motion to the carriage and through said carriage to said positioned blade. 5

3. In a safety razor, in combination, a handle, a fixed base mounted on said handle, safety guards extending laterally on opposite sides of said fixed base, a friction roller rotatably mounted on said fixed base and having a cam groove intermediate the length thereof, a carriage slidably mounted on said fixed base beneath said friction roller, blade supporting surfaces on said carriage, a positioned blade supported by said supporting surfaces above the upper surface of the safety guards, a pin projecting upwards from said carriage engaging said cam groove, a cover plate, adapted to be closed down above the upper surface of said fixed base and said positioned blade, having an aperture therethrough through which said friction roller partially projects when said cover plate is in the closed position, whereby rotation of said friction roller by rolling contact with the skin of the user imparts a reciprocatory motion to the carriage and hence to said positioned blade. 15

4. A safety razor of the reciprocating blade type comprising, in combination, a blade supporting carriage, side members upstanding from said carriage, said side members having cut away portions at the extremities thereof, and a blade having an aperture therethrough, said upstanding side members adapted to project through said aperture and to form supporting surfaces for said blade thereby to prevent lateral movement of said blade. 30

5. In a safety razor of the reciprocating blade type, in combination, a fixed base, a friction roller having a cam groove therein mounted on said base, a reciprocable carriage slidably mounted on said fixed base, a blade supported by said carriage, said carriage being supported beneath said friction roller, a pin on said carriage, and means to reciprocate said blade, said means comprising the engagement of said pin with said cam groove. 40

6. In a safety razor, in combination, a handle, a fixed base of channel section mounted on said handle, safety guards extending laterally on opposite sides of said fixed base, spaced bearing supports projecting upwards from the base of said channel, a friction roller having a cam groove mounted between and supported at each end in said spaced bearing supports, a blade supporting carriage mounted within said fixed base channel on a surface located below said roller, surfaces on said carriage for supporting a blade above the upper surface of the laterally extending safety guards and for longitudinally locating the same, side members on said carriage for laterally locating said blade, a pin projecting upwards from said carriage for engagement with said cam groove in the friction roller and for imparting a reciprocating movement to the carriage in consequence of rotation of the friction roller, and a cover plate closable down above the upper surface of a positioned blade and engageable, when closed, with said fixed base. 50

7. In a safety razor of the reciprocating blade type, a blade supporting and blade locating carriage comprising vertically and longitudinally extending side members having cutouts at each end to form seatings for a positioned slotted 60

blade below the level of the upper edges of the side members, said cutouts and said side members coacting with the slot in the blade to hold the same against longitudinal and lateral placement, respectively.

8. A safety razor of the reciprocating blade type comprising, in combination, a fixed base of channel section, safety guards extending laterally on opposite sides of said channel, a carriage 10 slidably mounted within said channel and on the base thereof for engaging and reciprocating a non-flexed blade, a friction roller mounted on the base of said channel on supports located within an opening in said carriage and a positioned 15 blade, and means forming a driving connection between said cam roller and said carriage.

9. A safety razor of the reciprocating blade type comprising, in combination, a fixed base of channel section, safety guards extending laterally on opposite sides of said channel, a carriage 20 slidably mounted within said channel and on the base thereof for engaging and reciprocating a non-flexed blade, a friction roller mounted on the base of said channel on supports located within an opening in said carriage and a positioned 25 blade, means forming a driving connection between said cam roller and said carriage, and a cover plate closable down above the upper surface of a positioned blade and engageable, when closed, with said fixed base.

10. A safety razor of the reciprocating blade type comprising, in combination, a fixed base of channel section, safety guards extending laterally on opposite sides of said channel, a blade 5 reciprocating carriage located within said channel and slidably supported upon the base thereof, side members extending upwards from said

carriage and longitudinally of said channel so as to project through a correspondingly shaped aperture in a positioned non-flexed blade, a friction driven cam roller mounted upon the base of said channel on supports disposed between the upstanding sides of the carriage, means forming an operative driving connection between said cam roller and said carriage and a cover plate closable down above the upper surface of a positioned blade, coacting means for 10 holding said cover plate in the closed position, and an aperture in said cover plate to permit of the partial projection therethrough of the friction cam roller when said cover plate is closed.

11. A safety razor of the reciprocating blade 15 type comprising, in combination, a fixed base of channel section, safety guards extending laterally on opposite sides of said channel, a carriage slidably mounted upon the base of said channel, a pair of upstanding longitudinal side members 20 forming part of said carriage, a friction driven cam roller mounted on supports located between said side members and extending from the base of said channel, a flat unflexed blade of greater width than the channel and having an aperture 25 in it to fit over said upstanding side members to form a driving connection between the blade and the carriage, means forming an operative driving connection between said cam roller and said carriage, and a blade retaining cover plate, 30 closable down above a positioned blade and apertured to permit of the partial projection therethrough of the friction driven cam roller when said cover plate is closed.
